R. A. STRANAHAN.
SPARK PLUG.
APPLICATION FILED SEPT. 10, 1918.

Patented Aug. 19, 1919.

FIG. -1-

INVENTOR
Robert Allen Stranahan,
By C. Wm. Burse & Crampton,
His Atty.

UNITED STATES PATENT OFFICE.

ROBERT ALLEN STRANAHAN, OF TOLEDO, OHIO, ASSIGNOR TO CHAMPION SPARK PLUG COMPANY, OF TOLEDO, OHIO, A CORPORATION OF DELAWARE

SPARK-PLUG.

1,313,425.

Specification of Letters Patent.

Patented Aug. 19, 1919.

Application filed September 10, 1918. Serial No. 253,366.

To all whom it may concern:

- Be it known that I, ROBERT ALLEN STRANAHAN, a citizen of the United States, and a resident of Toledo, in the county of Lucas and State of Ohio, have invented a certain new and useful Spark-Plug; and I do hereby declare the following to be a full, clear, and exact description of the invention, such as will enable others skilled in the art to 10 which it appertains to make and use the same, reference being had to the accompanying drawings and to the characters of reference marked thereon, which form a part of this specification.
- 15 This invention relates to the manufacture of spark plugs and particularly to the manner of securing the electrode terminal caps or heads to the outer ends of the porcelains carrying the same.
- 20 Considerable difficulty from the breakage of porcelains has been experienced in the manufacture of spark plugs employing porcelain insulators and having electrode terminal caps at their outer ends which fit over 25 the outer porcelain ends and are firmly compressed at their inner edges under retaining shoulders on the porcelains, such breakage occurring from the compressing force applied to the cap edges. Porcelains vary 30 more or less in size and this, together with the constant positive compressing action of the cap applying machines causes quite a large percentage of breakage of porcelains.
- To overcome such liability to breakage 35 the caps in some instances have been cemented on the porcelains or insulators. Such practice has been found objectionable, however, as different cements heretofore employed for the purpose have contained a 40 fairly high percentage of moisture and when a cap and porcelain cemented together thereby are subjected to a drying treatment, the outer edge portion of the cement first dries, thereby forming an edge seal and en- 45 trapping the remaining moisture within the cap. It is found that no amount of drying will eliminate this moisture and if the baking or drying temperature is raised sufficiently high the entrapping moisture forms 50 into steam and leaves the cement structure decidedly porous.

The object of my invention is the pro-

tection of a cement agent between the cap and porcelain of a spark plug, which agent when subjected to the required drying or baking temperature has no tendency to seal at the point where the lower edge of the cap and porcelain come together and which obviates the other objection incident to the use of cements heretofore used for the purpose. 60 Other advantages of the invention will be apparent from the following description.

The invention is fully described in the following specification and illustrated in the accompanying drawing, which is a central 65 longitudinal section of a spark plug embodying the same.

In the drawing, 1 designates the customary center electrode carrying porcelain of a spark plug, 2 the center electrode, 3 the 70 terminal cap or head therefor, which fits over the outer end of the porcelain and is compressed at its inner edge under a retaining shoulder 4 on the porcelain, and 5 a cementing agent between the porcelain and 75 cap.

This invention consists in the use of a cement between the cap and porcelain, which cement is not only adapted to fill any voids or spaces therebetween and is practically 80 free from moisture in its composition, but is also sufficiently compressible or resilient in its nature to prevent a breakage of the porcelain when the terminal cap edge is forcibly compressed thereagainst and the porcelain 85 is slightly over size, or the edge of the cap of greater thickness than customarily. In such case the compressibility of the cement compensates for the variation in size. It is found that the cementitious compound 90 known to the trade as "bakelite" is particularly adapted for this use, and that it reduces to a minimum the breakage of porcelains in the compressing of terminal caps thereon. "Bakelite" is the trade name for 95 a resinous condensation product, being sometimes termed "condensite", and is formed by chemically condensing together phenols and an aldehyde.

Having thus described my invention, 100 what I claim as new and desire to secure by Letters Patent is:—

1. In a spark plug, a center electrode carrying insulator, a metal terminal mem-

ber for said insulator, and a resinous condensation product cementing said member and insulator together.

2. In a spark plug, a center electrode carrying insulator, a terminal cap fitting over an end thereof, and a resinous condensation product cementing the cap and insulator together.

3. In a spark plug, a center electrode carrying insulator, a terminal cap fitting 10 over an end thereof, and a cement of bakelite between the cap and insulator.

In testimony whereof, I have hereunto signed my name to this specification.

ROBERT ALLEN STRANAHAN.
